RAIL LUBRICATOR

Albert F. Huber and John V. Houston, Chicago,
Ill., assignors to The American Brake Shoe and
Foundry Company, New York, N. Y., a corpora-
tion of Delaware

Application February 27, 1939, Serial No. 258,657

8 Claims. (Cl. 184—3)

The invention relates to railway track equipment and, more particularly, to a lubricating device for lubricating the flanges of passing vehicle wheels.

According to a preferred form of the invention, the lubricator is made up of a lubricant-applying device attached to the inside of the running rail and a combined reservoir and feeding device attached to the ends of the ties for supplying lubricant to the applying device.

In the preferred form, the applying device comprises essentially a delivery plate clamped to the web of the running rail in spaced relation so as to form a stationary slot under the head of the rail. A ramp bar having a lubricant-applying recess, and which may also act as a valve plate, is slidably mounted against the delivery plate. A housing member encloses the ramp bar and supports springs for yieldably holding the ramp bar in upper position to be engaged by wheel flanges.

The combined reservoir and feeding device, in its preferred form, comprises a comparatively large cylinder or pot with a weighted piston on top of the lubricant. Springs are provided for supporting the pot from the ends of adjacent railway ties in overhanging relation. A lever fulcrumed between the railway ties has one end bearing against the underside of the running rail and the other end applied to the supporting springs in such manner that the vertical movement of the rail caused by passing vehicles will agitate the lubricant cylinder, causing lubricant to flow into the applying device.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a plan view of the lubricating device, with parts broken away;

Fig. 2 is a section on the line 2—2 of Fig. 1;

Fig. 3 is a side elevation, with parts broken away, taken on the line 3—3 of Fig. 2;

Fig. 4 is a section on the line 4—4 of Fig. 1;

Fig. 5 is a transverse section taken on the line 5—5 of Fig. 3, but showing the ramp plate depressed by a wheel;

Fig. 6 is a transverse section taken on the line 6—6 of Fig. 3; and

Fig. 7 is a section showing a modification corresponding to Fig. 5, but with the ramp plate in upper position.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and, more particularly, to Figs. 1 and 2, the running rail denoted by 10 is supported on the usual tie plates 9, resting on the usual wooden railway ties 11 and is held down in any conventional way, as by spikes 8. The lubricant-applying device is denoted by 12 and is applied to the inside or gauge side of the running rail 10. The reservoir is denoted by 13 and supplies lubricant to applying device 12 through flexible connecting pipe 14.

Referring now to Figs. 3—6, the lubricant applying device 12 comprises a delivery plate 15 machined to fit the base flange 16 of the running rail 10 and spaced from the web 17 and head 18 of the running rail 10 by a U-shaped gasket 19 (Fig. 4) and spacers or shims 20. The gasket 19 has bent projections 22 and the spacers have bent flanges 21 extending up under the head 18 of the running rail, as shown more particularly in Figs. 4 and 6.

The U-shaped gasket 19 forms a lubricant chamber 23 with a discharge passage or port 24 under the head 18. The delivery plate 15 has an integral rib 26 tapered vertically as shown in Fig. 4 and horizontally as shown in Fig. 1 to evenly distribute the lubricant through the length of delivery slot 24. The lubricant is supplied through supply nipple 27 threaded into delivery plate 15 under the middle of equalizing rib 26. The supply nipple 27 is provided with an elbow 28 connected through a suitable coupling to the flexible feed pipe 14 (Figs. 1 and 2).

The valve plate 30 has sloping end surfaces 31 and 32 (Fig. 3) and a flat intermediate surface 33. It has an open top longitudinal recess 34 coextensive with the delivery slot 24 and has

a smooth faced side flange 35 engaging the smooth surface of delivery plate 15 and the lower edge of the rail head 18 which is substantially flush with the delivery plate 15.

The valve plate 30 is provided with depending flanges 36, forming recesses for helical springs 37 resting about positioning lugs 38 on platforms 39 secured to housing plate 42. The platforms 39 also rest on the base flange 16, as shown especially in Figs. 5 and 6. The valve plate 30 has guide lugs 43 slidably mounted in grooved ways 44 in the delivery plate 15 (Figs. 3 and 6). The helical springs 37 yieldably urge the valve plate 30 upwardly, the upward movement being limited by the engagement of lugs 43 against the rail head 18.

The housing 42 is of box-like construction, having end ears 45 through which pass bolts 46. The bolts 46 also pass through spacers 20, delivery plate 15 and web 17 to tightly clamp the entire lubricant applying assembly to the running rail.

The housing plate 42 is provided with a longitudinal groove seating an elongate leaf spring 47 bent away from the rail at its ends and at the middle, thereby providing intermediate portions pressing against the flanges 36 of the valve plate 30 and holding this plate snugly against the delivery plate 15 and in sliding relation thereto.

Referring now to the supply reservoir 13, this comprises a relatively large cylinder 51 having a detachable cover 52 held in position by detachable fastenings 53. A weighted piston 54 is fitted into the cylinder resting on lubricant 55. The piston 54 is provided with a handle 57 and an opening having a screw threaded removable plug 58 to facilitate removal of the piston 54 for replenishing lubricant. A helical spring 56 may be positioned in a central recess in the top of piston 54, acting between the cover 52 and piston 54 to urge the latter downwardly.

The bottom of the cylinder 51 is provided with a fitting 59 connected to a valve 60, which in turn is connected to the flexible hose 14. The valve 60 may be regulated manually to adjust the flow of lubricant through the delivery pipe 14.

Cylinder 51 is supported on a heavy bar 63, which in turn is supported by the bent ends 64 of leaf springs 65 bolted to adjoining ties 11 by bolts 66.

To agitate cylinder 51 to cause lubricant flow, a bar 67 is secured to the leaf springs 65 and a fulcrum bar 68 is secured to the railway ties 11. Agitator lever 69 has a pivot connection 70 with fulcrum bar 68 and has a bent end 71 engaging the underside of base flange 16 and a bent end 72 engaging the underside of the bar 67.

The lubricant feeding arrangement operates as follows: It is well recognized that both running rails and ties yield with a wave-like motion as the vehicle progresses along the track, but in most cases there is more relative movement between the running rails and the railway ties than between the latter and the road bed. It is the relative movement between the running rail 10 and the ties 11 which causes reciprocation of the agitator lever 69, which in turn applies a shaking or agitation to the reservoir 13, the springs 65 permitting the reservoir 13 to move with respect to the railway ties 11 in practice. The weight of piston 54 and the strength of spring 56 will be selected to give the desired lubricant flow according to the agitation caused by the passage of railway vehicles. The

valve 60 is for the purpose of making adjustments to meet varying conditions, such as the amount of agitation, the type of lubricant, temperature, the condition of the road bed, etc.

The operation of the lubricant applying device is as follows: The reservoir 13 and agitation system keeps the lubricant in chamber 23 under pressure. Normally, with no traffic, the valve plate 30 is in upper position, as shown in Fig. 6 and by the dotted lines A in Fig. 5, thus effectively sealing the discharge slot 24. As a vehicle approaches, the flanges 76 of the wheels engage the ramp surfaces 31 or 32 of the valve plate 30 according to the direction of travel of the vehicle, moving the valve plate downwardly against the springs 37, thereby bringing the applying slot 34 and delivery slot 24 in substantial alignment, as shown in Fig. 5. A limited amount of lubricant flows into applying slot 34 which is carried upwardly by the valve plate 30 as the wheel flange 76 leaves the valve plate 30, the lubricant being applied to the gauge surface of the rail head where it may be picked up by the wheel flanges of succeeding wheels.

In case there is sufficient pressure on the lubricant and it is of the right consistency, sufficient lubricant may flow into the applying slot 34 when the valve plate 30 is in its lower position indicated in Fig. 5 to cause an excess of lubricant to flow out of applying slot 34 to apply lubricant directly to the outer surface of the wheel flange, as will be apparent from Fig. 5.

Each time a wheel leaves the valve plate 30, the latter rises and closes delivery slot 24, and each time a wheel flange approaches the valve plate 30, the above-recited sequence of events is repeated, thus making the amount of lubricant applied proportional to the number of wheels passing over the lubricator. The agitation of the reservoir 13 is also proportional to the number of wheels passing over the lubricator.

Thus, the above described lubricator applies lubricant to both the gauge surface of the rail head and to the outer face of the wheel flanges. The lubricant is applied in such way that it is not spattered and cannot get on the wheel treads 75 to interfere with traction. Different types of oil or grease may be used, but it is preferable to use a relatively heavy grease, sufficiently heavy so as not to run down off the gauge surface of the rail, but sufficiently light to flow under agitation.

The above lubricator is safe and reliable. The lugs 43 limit the upward movement of the valve plate 30, the guides 44 being sufficiently large to prevent free vertical movement of the lugs 43 without binding. The long leaf spring 47 keeps the valve plate 30, when in upper position, against the face of delivery plate 15 and lower edge of the rail head 18 so as to keep delivery port 24 closed. The delivery plate 30 having ramp surfaces 31 and 32 on both ends, the lubricator can handle traffic in either direction. The slopes of the ramp surfaces 31 and 32 are sufficiently gentle so as to cause relatively slow downward and upward movement of the valve plate 30.

The reservoir pumping mechanism is simple, there being few moving parts. The feed can be easily adjusted by valve 60 and the reservoir is easily inspected and replenished with lubricant. To replenish, it is only necessary to remove the cover 52 and lift out the piston 54 by handle 57. Before removing piston 54 plug 58 is removed to avoid creating vacuum in the

bottom of cylinder 51 to interfere with the removal of piston 54.

Referring now to Fig. 7, if desired, the applying slot, indicated by 134 in this figure, may be made sufficiently deep so that it is in communication with the delivery slot 24 at all positions of the ramp plate 30. Thus, the plate 30 does not act as a valve plate and has no control over the lubricant feed which, in this case, is controlled entirely by the operation of the reservoir 13 and valve 60.

It will be understood that different reservoir and pumping devices may be used with the lubricant applying device and that different lubricant applying devices may be used with this reservoir and pumping device.

While certain novel features of the invention have been disclosed and are pointed out in the annexed claims, it will be understood that various omissions, substitutions and changes may be made by those skilled in the art without departing from the spirit of the invention.

What is claimed is:

1. In a track lubricator for use with a rail having a head, web and flange, a delivery plate, means spacing said delivery plate from said web to form an elongate delivery slot between said head and plate, an applying bar having inclined ramp surfaces on the ends thereof and having an open top elongate applying recess adjoining said head, said delivery plate having vertical groove-ways, said applying bar having lugs in said ways, a housing plate having spring supports, springs operating between said supports and said bar, means for clamping said housing and delivery plates to said rail with said applying bar slidably located between said housing and delivery plates.

2. In a track lubricator, a rail having a lubricant-applying device associated therewith, ties supporting said rail, a supply reservoir in the form of a cylinder, flexible strips attached to and projecting beyond the ends of adjacent ties, a supporting bar extending between said strips, said cylinder resting on said supporting bar beyond the ends of said ties, a weighted piston in said cylinder, a spring between the upper end of said cylinder and said piston, a flexible conduit connecting the lower end of said cylinder with said lubricant-applying device, a fulcrum support extending between adjacent ties, an agitator bar connecting said spring strips, a lever pivoted to said fulcrum support having one end under said rail, the other end under said agitator bar, whereby the wave motion of said rail with respect to said ties agitates said cylinder.

3. In a track lubricator, a rail having a lubricant-applying device associated therewith, ties supporting said rail, a supply reservoir in the form of a cylinder, a flexible support attached to an adjacent tie supporting said cylinder, a weighted piston in said cylinder, a conduit connecting the lower end of said cylinder with said lubricant-applying device, a fulcrum support attached to a tie, a lever pivoted on said fulcrum support and having one end in operative relation with said rail, the other end in operative relation with said cylinder, whereby the wave motion of said rail relative to said ties agitates said cylinder.

4. In a railway lubricator, a T-rail having a head, web and flange, a delivery plate disposed adjacent said web, spacers between the ends of said delivery plate and said web, a U-shaped gasket extending adjacent said spacers and the bottom of said delivery plate, forming a passage

between said delivery plate and said web and an elongate delivery slot under said head, an applying bar having oppositely inclined ramp surfaces and having an open top, elongate, lubricant-applying recess in its surface facing the side of said rail head and delivery plate, said applying bar having open sided spring recesses depending therefrom, said delivery plate having vertical groove-ways at its ends, said applying bar having lugs in said groove-ways, a housing plate having apertured ends surrounding the ends of said applying bar and forming with said delivery plate a housing for said bar, bolts passing through said apertured ends, said delivery plate, said spacers and the web of the rail, said housing plate having a longitudinal recess, a leaf spring in said recess engaging the adjoining side of said bar, said housing plate having platforms with centering projections, and coil springs resting on said platforms and disposed in said spring recesses for yieldably holding said bar in the path of wheel flanges.

5. In a railway lubricator, a rail having a head, web and flange, a delivery plate disposed adjacent said web, spacers between the ends of said delivery plate and said web, a gasket adjacent said spacers and the bottom of said delivery plate, forming a passage between said delivery plate and said web and a delivery slot under said head, an applying bar having oppositely inclined ramp surfaces and having an open top, lubricant-applying recess in its surface facing the side of said rail head and delivery plate, said applying bar having spring recesses depending therefrom, said delivery plate having vertical groove-ways, said applying bar having lugs in said groove-ways, a housing plate surrounding the ends of said applying bar and forming with said delivery plate a housing for said bar, said housing plate having a longitudinal recess, a spring strip in said recess engaging the adjoining side of said bar, said housing plate having supports, and coil springs resting on said supports and in said spring recesses for yieldably holding said bar in the path of wheel flanges.

6. In a track lubricator for use with a rail having a head, web and flange, a delivery plate providing an elongate delivery slot extending along said head, an applying bar having inclined ramp surfaces on the ends thereof and having an elongate applying recess adjoining said slot, said delivery plate and said applying bar having cooperating vertical guiding devices, a housing plate spaced from said delivery plate and forming an elongate space having spring supports at the bottom, springs operating between said supports and said bar urging said bar upwardly, means for clamping said housing and delivery plates to said rail with said applying bar vertically slidably located between said housing and delivery plates.

7. In a track lubricator for use with a rail having a flange, web and normal head, a delivery plate, means spacing said delivery plate from said web and head to form a lubricant chamber between said plate and web and a delivery passage between said plate and head, means supplying said lubricant chamber with lubricant, an applying bar having inclined wheel engaging surfaces on the ends thereof and having an applying recess in communication with said delivery slot to apply lubricant to the side face of said normal head, and means for holding said applying bar in operative position to permit up

and down movement thereof with respect to said rail upon passage of trains over said rail.

8. In a track lubricator for use with a rail having a flange, web and a normal head, a delivery plate, means spacing said delivery plate from said web and head to form a lubricant chamber between said plate and web and an elongate delivery slot between said plate and head, means supplying said lubricant chamber with lubricant, an applying bar having inclined 10 wheel engaging surfaces on the ends thereof and

having an elongate, applying recess in communication with said delivery slot to apply lubricant to the side face of said normal head, and means for holding said applying bar in operative position to permit up and down movement thereof with respect to said rail as the wheels of trains passing over said rail engage said wheel engaging surfaces.

ALBERT F. HUBER.
JOHN V. HOUSTON.
